Application April 14, 1958, Serial No. 50,452

Term of patent 14 years

(Cl. D74—9)

FIG.2.

FIG.3.

Fig. 1 is a front elevational view of a mailbox showing my new design;

Fig. 2 is an end elevational view; and

Fig. 3 is a front perspective view thereof as it appears in opened position.

The end opposite to that shown in Fig. 2 is substantially identical with the end shown except that the two ends are of course "right" and "left," while the back is plain and unornamented.

I claim:

The ornamental design for a mailbox, as shown and described.
